Primary Examiner — Cynthia Ramirez*Assistant Examiner* — Gino Colan(74) *Attorney, Agent, or Firm* — Gulf Coast Intellectual Property Group(57) **CLAIM**

The ornamental design for a trash receptacle, as shown and described.

DESCRIPTION

FIG. 1 is a left side view of the present invention in its extended position; and

FIG. 2 is a left side view of the present invention in its collapsed position; and

FIG. 3 is a right side view of the present invention in its extended position; and

FIG. 4 is a right side view of the present invention in its collapsed position; and

FIG. 5 is a top view of the present invention; and

FIG. 6 is a bottom view of the present invention; and,

FIG. 7 is a perspective view of the present invention.

The broken line showing a mailbox is included for the purpose of illustrating environment and forms no part of the claimed design.

The leash is shown with a symbolic break in its length. The appearance of any portion of the article between the break lines forms no part of the claimed design.

1 Claim, 4 Drawing Sheets---
